United States Patent

Des. 237,571
Patented Nov. 11, 1975

237,571

SHELF UNIT OR SIMILAR ARTICLE

Vernon E. Lane, Jr., 211105 Brooklawn Drive,
Dearborn Heights, Mich. 48127

Filed Mar. 28, 1974, Ser. No. 455,794

Term of patent 14 years

Int. Cl. D6—04

U.S. Cl. D6—186

FIG. 2

FIG. 1

FIG. 3FIG. 4FIG. 1 is a front perspective view of a shelf unit or similar article, illustrating my new design;

FIG. 2 is a top view thereof;

FIG. 3 is a front elevational view thereof; and

FIG. 4 is a right side view thereof.

The rear of the article is plain and unornamented.

I claim:

The ornamental design for a shelf unit or similar article, substantially as shown and described.
